UNITED STATES PATENT OFFICE.

AARON M. WEBER, OF NEW YORK, N. Y.

DESIGN FOR TRIMMING.

SPECIFICATION forming part of Design No. 37,249, dated November 22, 1904.

Application filed October 13, 1904. Serial No. 228,362. Term of patent 3½ years.

To all whom it may concern:

Be it known that I, AARON M. WEBER, a citizen of the United States, residing in the city of New York, borough of Manhattan, in 5 the county and State of New York, have invented a new, original, and ornamental Design for Trimming, of which the following is a specification, reference being had to the accompanying drawing, forming part thereof, o in which the figure is a perspective view of a strip of trimming, showing my new design.

What I claim as new, and desire to secure by Letters Patent, is—

The ornamental design for trimming, as shown.

AARON M. WEBER.
